Primary Examiner—Ian Simmons*Assistant Examiner*—R. Johnson(74) *Attorney, Agent, or Firm*—Sughrue Mion, PLLC(57) **CLAIM**

The ornamental design for an electronic piano, as shown and described.

DESCRIPTION

FIG. 1 is a perspective view of the top, front and left side of an electronic piano showing my new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a front elevational view thereof, with a cover for the piano keys shown in a closed position; and,

FIG. 9 is a top plan view thereof, with the cover shown in a closed position.

The portions shown in broken lines are for illustrative purposes only and form no part of the claimed design.
